UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

COMPOSITE HEEL.

Application filed January 3, 1922. Serial No. 526,552.

To all whom it may concern:

Be it known that I, JOHN B. HADAWAY, a citizen of the United States, residing at Swampscott, in the county of Essex and 5 State of Massachusetts, have invented certain Improvements in Composite Heels, of which the following description, in connection with the accompanying drawings, is a specification, like reference characters on the 10 drawings indicating like parts in the several figures.

This invention relates to heels and, more particularly, to the type of heel which is commonly called a composite heel, that is to 15 say, a heel having a rigid base section and a resilient, cushion top section.

A large proportion of the shoes manufactured today have composite heels. Commonly, the base section consists of one or 20 more lifts of leather or leatherboard and the top section is made of rubber. The usual practice in attaching heels of this character is to nail the base to the shoe at one operation and then to nail the rubber section to 25 the base and shoe in another operation, usually with a separate machine. This process is known as "double nailing." Some composite heels are attached at a single nailing by a process disclosed in the Standish 30 Patent, No. 1,288,253, dated Dec. 17, 1918 but, heretofore, this method has been used only in attaching comparatively low heels, for example, in heeling men's shoes.

In the manufacture of women's shoes requiring comparatively high heels, it is practically necessary to prick the heel before the attaching nails are driven. This is conspicuously true when, as is usually the case, the top lift is small in comparison to the base 40 lift of the heel. It is then desirable that the attaching nails be driven at an inclination to the tread face of the heel, and it is preferable that they diverge somewhat from the top lift toward the base, in order to provide 45 a solid and secure attachment. The double nailing process has always been considered necessary when the heel base was pricked, for the reason that it was impossible to locate the rubber top section upon the base 50 with sufficient accuracy to insure that the attaching nails driven through the rubber top section would enter the pricked nail guiding holes in the base.

The object of the present invention is to 55 provide a composite heel having nail guid-

ing holes in its base section which can be successfully and readily attached at a single nailing. By this invention it becomes a commercial possibility to realize the advantages and economies of single nailing in attaching 60 heels to women's shoes.

A feature of the invention consists in a heel having a base section provided with nail guiding holes, combined with a top section covering the holes, such, for example, as a 65 rubber or other similar resilient heel section. By locating the top section in exact predetermined relation to the holes in the base the points at which the attaching nails are driven may be located with accuracy and 70 their entrance into the guiding holes in the base may be assured.

To the end that the top section may be readily located with its washers in register with the pricked holes in the base, the two 75 sections are preferably formed with co-operating projections and depressions or other equivalent means for determining their relation to each other when assembled. In the illustrated embodiments of the invention the top section is, furthermore, provided with 80 means for facilitating its correct location with respect to the nails to be driven through it into the nail guiding holes in the base, and such means may conveniently consist of depressions or their equivalent in the tread face, which may serve to determine the location of the heel with respect to the holes 85 in the nailing die of a heeling machine.

As a further development of the invention 90 a composite heel is produced which is adapted for blind single nailing, and in this aspect it comprises a heel base section provided with nail guiding holes in combination with an imperforate top section in which washers 95 may be embedded and so covered with the rubber as to be invisible from the tread face of the heel.

Other features and advantages of the invention will be understood and appreciated 100 from reading the following detailed description in connection with the accompanying drawings which illustrate certain forms thereof which are specifically different but all of which embody the inventive idea.

In this specification and in the claims annexed thereto, reference is made to "leather" 105 and "rubber" as materials which may be employed for the base and top sections of the heel, respectively, but it should be clearly 110

understood that these words are used only in an illustrative sense. Where leather is mentioned it is to be understood to include leatherboard, fibreboard or any other equivalent suitable for use in the manufacture of heel bases, and where rubber is mentioned it is to be understood to include any resilient composition having the characteristics desirable in a cushion or resilient heel.

10 In the drawings,

Fig. 1 is a plan view of a composite heel embodying the invention in one form;

Fig. 2 is a cross section of the heel on the line 2—2 of Fig. 1;

15 Fig. 3 is a fragmentary, sectional view similar to Fig. 2 but showing a modification;

Figs. 4 and 5 are views similar to Figs. 1 and 3, respectively, illustrating another 20 modification; and

Figs. 6 and 7 are similar views of still another modification.

Referring now to the drawings, 10 indicates the rigid base section of a heel which 25 may be built up of lifts of leather, leatherboard or other suitable material and which has holes 12 pricked therein for guiding the heel attaching nails. A rubber heel section or lift 14 is placed on top of the base

30 10 and preferably temporarily attached thereto sufficiently to maintain the sections in undisturbed relation until the permanent attachment is effected by driving the heel attaching nails. 16 indicates the usual rubber

35 heel washer and 18 indicates a conical or other suitably shaped depression in the tread face of the rubber top section located coaxially with the washer, as is common in commercial rubber heels. As illustrated in Figs. 1, 2

40 and 3, projections or protuberances 20 are molded on the inner face of the rubber heel section 14 in predetermined fixed relation to the washers 16 and 18. Recesses 22, corresponding in number and arrangement to

45 the protuberances 20, are formed in the top of the base section and are accurately located in the same predetermined relation to the pricked holes 12 as that between the protuberances 20 and the washers and de- 50 pressions 16, 18. These recesses 22 may conveniently be formed with short awls in the heel pricking machine at the same time the holes 12 are pricked; in this way it is easy to

55 secure exact and uniform relation between the depressions 22 and the pricked holes 12 in all heels. In assembling the base and top sections the protuberances 20 are readily inserted in the recesses 22 and exact register of the holes in the washers 16 with the holes

60 12 pricked in the base beneath is positively assured, so that when the attaching nails are driven through the washers they cannot fail to enter the nail guiding holes 12 in the base. If the protuberances 20 are made

65 to fit sufficiently tightly in the recesses 22

their frictional engagement with the walls of the recesses will be ample to secure the heel sections in assembled relation without the use of cement, but cement may be used if desired. The nail guiding holes 12 are 70 usually pricked at an inclination to the top of the base and penetrate the base to a considerable depth, guiding the nails for a sufficient distance to insure against deflection from their proper paths. The holes 12 75 preferably diverge from the top toward the bottom of the base section, as clearly shown in Fig. 2, in order that the pattern of the nailing may cover as large an area as possible on the heel seat, to the end that a solid and secure attachment of the heel shall be effected. Although the rubber top section 14, when attached to the base, is imperforate and covers the nail guiding holes 12, the entrance of the attaching nails into the said 80 holes is assured by the positive register effected by the interlocking construction of the two heel sections. The depressions 18, or their equivalent, may co-operate with a correspondingly formed nailing die in a heelng machine and thus constitute means for determining the location of the heel with respect to the holes in the nailing die. 85

In the modification of the invention shown in Fig. 3, the bottom of the depression 18 is imperforate above the washer 16, providing a heel adapted for blind nailing. When the attaching nails are driven until their heads are seated upon the washers and the drivers withdrawn the rubber closes over the heads of the nails, which are invisible in the attached heel. 90

In the modification shown in Figs. 4 and 5, similarly disposed holes are formed in the adjacent faces of the heel sections 10 and 14 and metal or other pins 24 are employed to secure exact and positive register between the two heel sections. Otherwise the construction and arrangement are the same as in the form of the invention shown in Figs. 1 and 2. 100

In the modified form of the invention shown in Figs. 6 and 7 the base section 26 of the heel is formed of a single piece of comparatively hard rubber or other suitable composition or material to which the resilient top section 28 can be vulcanized. The nail guiding holes 30 in this base may be formed in the vulcanizing mold and the depressions 32 in the tread face of the top section 28 are formed by the mold, in register with the said holes. This form of heel may be attached in the same manner as those previously described, except that the attaching nails will be driven down until their heads are seated on the top of the relatively hard base section 26 where they will have sufficient holding power for secure attachment. No washers are required in this 110 120 125 130

form of heel and the soft rubber of the top section 28 closes over the heads of the nails, producing a blind nailed heel.

It will be understood from the preceding disclosure that, by the present invention, a composite heel has been produced which can be satisfactorily and economically attached to women's shoes or used under any other circumstances requiring a pricked heel and that such a heel can be readily attached at a single nailing, a result never heretofore attained in the art.

Having described the invention, what is claimed as new and desired to be secured by Letters Patent is:—

1. An unattached heel comprising a base section provided with inclined holes for guiding attaching nails, and an attached top section covering the holes and located in predetermined relation thereto.
2. An unattached heel consisting of a base section provided with empty nail guiding holes and an imperforate top section.
3. A heel comprising a base section provided with nail guiding holes, and a top section having depressions in its tread face in register with said holes but not communicating therewith.
4. A composite heel comprising a pricked base section and a resilient top section, the top section being imperforate and having washers embedded therein in register with the holes pricked in the base.
5. A composite heel, adapted for blind single nailing, comprising a rigid pricked base, and a resilient top section having washers embedded therein in register with the pricked holes in the base, the washers

being invisible from the tread face of the top section. 40

6. A composite heel comprising interlocked base and top sections, the base section being provided with nail guiding holes and the top section having means in predetermined relation to said holes for determining the location of the heel with respect to the holes in the nailing die of a heelng machine. 45

7. An unattached heel comprising a comparatively high base section provided with nail guiding holes penetrating to a considerable depth, and a top section having means for facilitating the correct location of nails to be driven therethrough into the holes in the base section. 50

8. A multi-section heel comprising a base section provided with inclined nail guiding holes, and a superposed top section having means at its tread face for determining the locations of the entrances to said holes. 55

9. A multi-section heel comprising a base section provided with divergent nail guiding holes, and a superposed top section having means at its tread face for determining the locations of said holes. 60

10. A heel comprising a pricked base section, a resilient top section having nailing location indications identical in arrangement with the pricked holes in the base, and means for positively determining the location of the top section upon the base with said indications in register with said holes. 65

In testimony whereof I have signed my name to this specification.

JOHN B. HADAWAY.
